CLAIM

The ornamental design for a vehicle seat, as shown and described.

DESCRIPTION

FIG. 1 is a top view of a vehicle seat;

FIG. 2 is a front view thereof; and,

FIG. 3 is a left side view thereof and a mirror image of a right side view.

The bottom and rear of the vehicle seat are not visible during normal use.

The logo in the center of the vehicle seat headrest forming part of the claimed design is registered trademark No. 7,656,432, owned by Gordon Murray Group Limited.

1 Claim, 3 Drawing Sheets
